(57) **CLAIM**

The ornamental design for a light-emitting diode, as shown and described.

DESCRIPTION

FIG. 1 is a perspective view of a light-emitting diode showing our new design;

FIG. 2 is another perspective view of the light-emitting diode;
FIG. 3 is a front elevational view of the light-emitting diode;
FIG. 4 is a rear elevational view of the light-emitting diode;
FIG. 5 is a left side view of the light-emitting diode;
FIG. 6 is a right side view of the light-emitting diode;
FIG. 7 is a top plan view of the light-emitting diode; and,
FIG. 8 is a bottom plan view of the light-emitting diode.
The broken line showing is for the purpose of illustrating environmental structure and forms no part of the claimed design.
